UNITED STATES PATENT OFFICE.

HARVEY A. GARNER, OF MILWAUKEE, WISCONSIN.

COMPOSITION SHINGLE.

Application filed October 12, 1928. Serial No. 384,100.

This invention relates to composition shingles, and more particularly to the means for connecting together the shingle units.

Composition shingles as now produced commercially, are formed in units of four or more, and in shingling a roof or the like the adjacent ends of the units are adapted to abut, the joint or connection being covered by the next row of shingles which over-
laps the under row and covers these abutting ends.

However, should the shingles either curl up or be blown up by the wind, the joint formed by the abutting ends of the shingle units is left exposed, thereby permitting rain to pass therethrough.

This present invention is particularly designed to overcome this known objection and to provide a composition shingle so constructed that the joint or connection between the adjacent ends of the shingle units is at all times protected against such a deficiency, and this known objection eliminated.

The particular construction of this invention, as well as the advantages inherent herein, will be made more apparent as the description proceeds, especially when considered in connection with the accompanying drawings.

In the drawings:

Fig. 1 is a plan view of a plurality of shingles constructed and assembled in accordance with this present invention;

Fig. 2 is an enlarged sectional view, taken on the plane indicated by the line 2—2 in Fig. 1;

Fig. 3 is a fragmentary perspective view of one end of one of the shingle units; and,

Fig. 4 is an enlarged detail sectional view, showing the connection between two shingle units.

Referring now more particularly to the drawings wherein like reference characters indicate like parts, it will be seen that the reference character 10 indicates a composition shingle unit or section which, as illustrated, consists of four shingles 11. Obviously the number of shingles forming a section or unit may be varied.

Each section of shingle is provided with a thin end portion or lip 12 which is adapted to engage a similar portion formed on the adjacent end of the next section of shingles. As is clearly shown in Fig. 1, one of the lip portions 12, for example, the left

hand one, as viewed in the said figure, is of a width substantially equal to that of one of the notches which separate the individual shingle members 11, while the other or right hand lip member of each section is of a substantially greater width so that it projects somewhat beneath the main body portion of the left hand shingle 11 of the adjacent strip. By reference to Fig. 4, it will be seen that while the thin end portion or lip 12 on one section of shingle is disposed adjacent the back thereof, the lip of the other section with which it is adapted to cooperate is disposed adjacent the front thereof, so that together they make a half and half joint. In practice this joint is adapted to be cemented together, the cement material being indicated by the reference character 13 in Fig. 4.

As illustrated in Fig. 1, the sections of shingle, when laid, are disposed so that the overlying lip portions 12 are staggered and disposed under a shingle of the next overlapping line of shingles. In this manner the joints between the sections of shingles are covered and protected, but irrespective of this method of laying the shingles, the connection between the sections of shingle provides a permanent joint, thereby preventing the passage of water therethrough, even though the overlapping line of shingles has been curled upwardly by the rain or sun. Thus a watertight roof is provided.

Obviously a shingle constructed in accordance with this invention may be quickly and easily laid and a thorough waterproof covering provided. Obviously while the invention is described and illustrated as relating particularly to shingles formed of composition material, it will be apparent that the sections of shingle may be constructed of any suitable material. In a like manner the number of shingles comprising a section unit may be also varied.

To this end reservation is therefore made to make such changes in the specific form of the invention described and illustrated herein as may come within the purview of the accompanying claims.

Having thus described the invention what is claimed is:

1. A composition strip shingle comprising a substantially rectangular strip one edge of which is provided with a plurality of spaced notches, and the ends of which are each provided with a lip portion of reduced thick-

2
ness, one of said lip portions being flush with one surface of the strip and of a width substantially equal to that of said notches, and the other of said lip portions being flush 5 with the other surface of the strip and of a width greater than that of said notches.

2. A composition shingle roof comprising a plurality of multiple-shingle strips, arranged end to end in overlapping rows, one 10 edge of each strip being provided with a

plurality of spaced notches, and the ends thereof being each formed with a lip portion of reduced thickness, one of said lip portions being flush with one surface of the strip and the other lip portion flush with 15 the other surface, and one of said lip portions being of a greater width than the other.

In testimony whereof, I affix my signature.

HARVEY A. GARBER.
